UNITED STATES PATENT OFFICE.

HENRY T. ADAMS, OF CHICAGO, ILLINOIS.

ADJUSTABLE RING BOOK.

Application filed April 13, 1925. Serial No. 22,811.

This invention relates to adjustable ring books and the like and is fully described in the following specification and shown in the accompanying drawing, in which:

5 Figure 1 is an end elevation of the ring book embodying the invention;

Fig. 2 is a front elevation of the back strip showing the rings therein;

10 Fig. 3 is a section showing the ring in open position;

Fig. 4 is the same showing the ring in closed position; and

15 Fig. 5 is a partial section on the line 5—5 of Fig. 4.

20 The embodiment illustrated comprises a metal back strip 10 which is preferably flat and has rolled edges 11, 12, the latter being preferably round in cross-section and uniform from end to end. These edges are not 25 completely closed but have an opening 13 which runs therethrough the length of the strip.

25 A U-shaped ring 14 which is preferably made from sheet metal and placed so that the cross-section of this ring is rounded near the center as shown in Fig. 5. One end of this ring terminates in an elongated guide 15 which is curled outwardly and upwardly at 16 so as to interlock with either of the 30 rolled edges 11, 12 and to be freely slidable longitudinally therethrough.

35 The free outer end of the ring 14 is provided with a hook 17 which, when the ring is placed therein into closed position as shown in Fig. 4, snaps into the recess 13 thereby locking the ring 14 in closed position, the stiffness of the ring holding it 40 closed and providing sufficient friction between the ends 16 and 17 and the rolled edges 11, 12 to prevent the rings 14 being readily moved along the grooved strip 10.

45 Covers 18, 19 may be attached to the grooved strip 10 in any desired manner, as by means of a flexible cloth strip 20 which may be secured to the back strip 10 by means of rivets 21 or the like.

50 Thus it will be seen that a convenient ring book is provided in which the rings may readily be removed therefrom or moved from one position to another on the back to accommodate sheets having different spacing of holes therein, this device is also very economical of space, the height of the rings from the back of the book being reduced 55 to a minimum.

This arrangement permits as many rings

as are desired to be used at the same time and with any desired spacing to suit the spacing of the holes in the sheets used. It will also be noted that the rolled edges are 60 identical on the two sides so that the U-shaped members may be used on either side or, if desired, on both sides at the same time.

While I have shown and described but a single embodiment of this invention, it is to 65 be understood that it is capable of many modifications. Changes therefore in the construction and arrangement may be made which do not depart from the spirit and scope of the invention as disclosed in the 70 appended claims.

I claim:

1. In a ring book, a metal back strip having inturned edges, and a U-shaped member adapted to have one end interlock with 75 one of said edges and to be swung about said interlocked edge so that the other end is brought into engagement with the other edge.

2. In a ring book, a metal back strip having inwardly curved edges, and a U-shaped member adapted to have one end interlock with one of said edges and to be swung about said interlocked edge so that the other end is brought into engagement with the 85 other edge.

3. In a ring book, a metal back strip having inturned edges, and a U-shaped member adapted to have one end interlocked with one of said edges at any point throughout its 90 length and to be swung about said edge so as to bring the other end into engagement with the other edge.

4. In a ring book, a metal back strip having inturned edges, and a U-shaped member 95 adapted to have one end interlock with one of said edges and to have the other end swung into engagement with the other edge, the outer end of said member being adapted to have locking engagement with said 100 other edge.

5. In a ring book, a metal back strip having inturned edges, and a U-shaped member having one end widened and adapted to have sliding engagement with one of 105 said edges and to be swung about said edge so as to bring the other end into engagement with the other edge.

6. In a ring book, a metal back strip having inturned edges, and a U-shaped member 110 adapted to have one end interlock with one of said edges and to have the other end

swung into engagement with the other edge, said U-shaped member being stamped from sheet metal.

7. In a ring book, a metal back strip having inturned edges, and a U-shaped member having one end adapted to have rocking engagement with one of said edges and having means for preventing lateral swinging of said member but permitting said member to swing into engagement with the opposite edge, the outer end of said U-shaped mem-

ber being adapted to lock with said opposite edge.

8. In a ring book, a sheet metal back strip having inwardly turned edges of uniform cross-section throughout, and a U-shaped ring member adapted to frictionally engage said edges at any point in the length of said strip.

In testimony whereof I hereunto set my hand this 6th day of April, 1925.

HENRY T. ADAMS.
